UNITED STATES PATENT OFFICE.

FRANK EDWIN ANDERSON, OF BROOKLYN, NEW YORK.

STAMPING DEVICE.

1,271,826.

Specification of Letters Patent. Patented July 9, 1913.

Application filed January 20, 1917. Serial No. 143,495.

To all whom it may concern:

Be it known that I, FRANK E. ANDERSON, a citizen of the United States, residing in the borough of Brooklyn, in the county of 5 Kings, city of New York, and State of New York, have invented certain new and useful Improvements in Stamping Devices, of which the following is a specification.

My invention relates to stamping-devices, especially to those in which the type-face or printing-surface is formed of soft-rubber; and my said device, herein disclosed, is of an exceedingly simple and cheap form of construction, easily operated, and self-inking; 10 and while not limited to such use, as shown, described and claimed herein, it is so formed and constructed as to be especially adapted for use in stamping upon eggs, the dates of insertion in cold storage, etc., or other desired data; such dating, especially, being now required in several States by law or regulation, before such eggs can be placed in storage.

My said invention is fully shown and described in the following specification, of which the accompanying drawing, forms a part, wherein similar letters or numerals of reference designate like or equivalent parts, wherever found throughout the several 25 views; and in which:

Figure 1, is a top plan-view of my improved egg-stamping device;

Fig. 2, is a side view thereof looking from the bottom of Fig. 1, in the direction of the 30 arrows; and

Fig. 3, is a front view of the stamp-block, in central vertical section, taken on substantially the central line 3—3 of Fig. 1, looking toward the right in the direction of the arrow; and

Fig. 4, shows diagrammatic views of the stamp-block, (and inking-pad) in five different relative positions marked A, B, C, D and E.

Referring to the drawing:

The reference numeral F designates a suitable base-piece of wood or metal, to which is secured by the bolt 1, the lever-standard 2, having at the top the lever holding slot 50 between the top extensions 2', in which, upon the pivot-bolt 4 passing through the upper extension 2', of such lever-standard, is pivotally mounted the stamp-carrying rock-lever composed of the double-bar rear

lever portion L', and the open ended yoke 55 L, the pieces 3, of L', being formed into a rigid bar by rivets 4'; by spot-welding or in any other desired manner; and in the yoke L, there is revolvably mounted the hollow cylindrical stamp-block G, carrying at 60 either end a printing surface. Such block G, having centrally diametrically passing through the same the cam-shaft 5, secured together so that the two will rotate in unison by a pin 21, or in any other desired manner, 65 such cam-shaft 5, having formed integral therewith at one side, the throw-cam 6, of substantially the shape shown having the rounded ends 6' and 6'' and the concavities or retaining faces 18. The journal ends 22, 70 and 22' of the shaft 5 extend beyond the block and throw-cam as clearly indicated in Figs. 2 and 3; which ends spring into position in suitable journal perforations formed in the ends of the yoke L, as clearly shown 75 in Figs. 1 and 2, where it will be revolvably held by the natural resiliency of the side-pieces 3' of such yoke.

The stamp-block G is usually and preferably of the form shown in detail, and in 80 central longitudinal section in Fig. 3, comprising the central cylindrical main or body-portion 10, having the smaller diameter, like cylindrical stamp-holding end portions 11, usually and preferably provided with the 85 annular stamp-securing exterior-grooves 12. And such end extensions 11 are each provided with a concavity 13; which concavities are connected by the central passage 13'. The stamps I and I' are formed usually of 90 flexible-rubber or other suitable material, to comprise the central concave-faces 14, from which extend backward the annular securing-flanges 15, having the beads 30 to fit into the grooves 12 of the block 10. The 95 face 14, of the concavity, is provided with a date or any other data, but in this case, to indicate the type-face molded in the rubber, I have used the word "eggs." The central rear securing cavity of the stamp, 100 formed by the flanges 15, of the rubber printing-face of the stamp, is of a slightly smaller diameter than are the cylindrical holding ends 11, of the stamp-block, so that when placed in position thereon, as clearly 105 indicated in Figs. 2, 3 and 4, such stamps will be held in place upon either end of the stamp-block G by the natural resiliency of

such annular soft rubber securing flange 15 and the coöperation of the beads 30 with the grooves 12.

The yoke-lever L and L' has attached to 5 the rear the lift-spring 16, secured at the bottom to the screw or other pin 17, secured in the end of the base-piece F, so as to maintain the forward end of the yoke-lever carrying the stamp G, in the raised, ready for 10 printing, position shown in Fig. 2, and in Fig. 4 at A.

The throw-cam 6 is of practically figure 15 S exterior form, being provided with rounded ends 6' and 6'' and stop-faces 18, concaved as shown, in which fit the convex outer-end front stop-face 19, of the cam-pawl 7; immediately above the throw-hook 20.

The head-portion 19 and 20 of the throw-lever 7 passes up within the yoke on either side, usually the one shown, as indicated in Figs. 1 and 2; and is held in position against the throw-cam 6, by a suitable coil or other spring 23, secured at the other end 25 to a screw 24, in the block F, all as clearly indicated in Figs. 1 and 2.

Secured in position usually in a cavity formed in the base-block F, immediately below the stamp-block G, is an inking-pad 30 K, usually of the well-known rubber-stamp self-inking type.

Rubber-stamp faces I and I' are as before indicated in this type of apparatus used for marking eggs; slightly concaved; so as to fit the contour of the side or end of the egg, to be marked; and such stamps of my improved form, are usually placed in front of the candler, and adjacent to the candling-lamp; and one of the faces, which are of course identical, having been inked, and the stamp-block given a half revolution, the candler then candles the egg, and quickly presses the side thereof down into the concaved top flexible rubber printing-head surface 14 of the top printing face I, as indicated by the dotted lines in Fig. 2; and this pressing the stamp down upon the inking pad K, when the under printing stamp I, comes in contact with such inking-pad; and sufficient pressure is brought upon the egg to imprint the legend upon I thereon, this forces inward the top concave printing surface 14, and the consequent compression of the air in the concavities 13, connected by the central air passage 13' will tend to force the face of the bottom rubber-type member I' outward into a convex form, as shown in dotted lines in Fig. 3, upon the ink-pad K, which, is usually of the rounded form shown and the same will be consequently thoroughly inked.

When in the raised position, and inked ready for operation, the throw-pawl 7, is in the position shown in Figs. 2 (and 4 at A); 65 with the securing front-face 19 in contact

with the rear concaved-face 18, of the throw-cam 6; and when thrown down into the printing and inking position shown at B, of Fig. 4, the spring 23, will force the cam-pawl 7, up over the top rounded end portion 6'' of the throw-cam 6, until the same lies in the cavity 20 of the throw-hook of such cam-pawl 7, when the action of the spring 23 will throw the cam-pawl down over the same as clearly indicated at B; 75 and upon the release of the stamp-block G from pressure of the egg; the yoke, by the action of the spring 16, will, by the quick movement of the cam-pawl exerted on the cam, throw the printing-block G, a half 80 revolution to the rear, into the position shown in Fig. 1, such motion and action and the various positions assumed by such stamp-block, throw-cam and throw-pawl during such reversal, all being clearly indicated in Fig. 4, whereby the just inked bottom-pad I' will be brought to the top to receive the next egg, while I, will be in position to be inked upon the printing of such egg, and this operation is repeated indefinitely whereby a much greater number of eggs may be candled and stamped than by the devices now used in a given time.

The upward throw of the stamp is limited by the contact of the stop-pin 25, of the yoke-lever L', against the rear of the bracket 2, as clearly indicated in Figs. 1 and 2.

It is evident that many changes and modifications in the construction of my improved stamping device, and many of the parts thereof, may be made, without departing from the scope of my invention; and I do not intend to limit myself to the exact construction of the parts thereof herein shown.

I claim:

1. In a stamping-device, a supporting base-piece; a spring-retracted pivoted throw-lever having a yoke; a stamp-block of cylindrical form carrying a printing-face, on either end revolvably mounted in and carried by the yoke of the throw-lever; a spring normally maintaining the throw-lever in a raised position; an inking-pad supported by the base-piece immediately below the yoke; and means for automatically reversing the stamp-block, so as to bring the newly inked bottom-printing surface upward; and the just used top-printing surface downward, upon the throwing of the throw-lever to its upward limit.

2. In a stamping-device, a supporting base-piece; a spring retracted throw-lever; a stamp-block of cylindrical form revolvably carried by the throw-lever, with smaller cylindrical end-portions carrying a printing-face on either cylindrical end-portion; a spring normally maintaining the throw-lever in a raised position; an inking-pad supported by the base-piece immediately below the yoke; and means for automatically re-

versing the stamp-block so as to bring the newly inked bottom-printing surface upward, and the just used top-printing surface downward, upon the throwing of the throw-lever to its upward limit.

3. In a stamping-device, a supporting base-piece; a spring-retracted pivoted throw-lever having a yoke; a stamp-block of cylindrical form carrying a concave printing face of soft-rubber having an annular-flange fitting over each end-portion, and held thereon by the resiliency of the flange, on either end revolubly mounted in and carried by the yoke of the throw-lever; a spring normally 10 maintaining the throw-lever in a raised position; an inking-pad supported by the base-piece immediately below the yoke; and means for automatically reversing the stamp-block, so as to bring the newly inked 15 bottom-printing surface upward and the just used top-printing surface downward upon the throwing of the throw-lever to its upward limit.

4. In a stamping-device, a supporting base-piece; a spring retracted pivoted throw-lever, having a yoke; a stamp-block of cylindrical form carrying a soft-rubber printing-face on either end; a cam-shaft or pin, revolubly securing the stamp-block in the 20 yoke of the throw-lever; a spring normally maintaining the throw-lever in a raised position; an inking-pad supported by the base-piece immediately below the yoke; a cam-pawl pivoted to the base, a spring normally 25 keeping the outer face of the pawl in contact with the cam, whereby, upon the throwing of the throw-lever to its upward limit, the stamp-block will be automatically reversed so as to bring the newly inked bottom 30 printing surface upward; and the just used top-printing surface downward.

5. In a stamping-device, a supporting base-piece; a spring retracted pivoted throw-lever, having a yoke; a stamp-block of cylindrical form carrying a soft-rubber printing-face on either end; a cam-shaft or pin having a substantially exteriorly figure 8 shaped cam revolubly securing the stamp-block in the yoke of the throw-lever; a 35 spring normally maintaining the throw-lever in a raised position; an inking-pad supported by the base-piece immediately below the yoke; a cam-pawl pivoted to the base, a spring normally 40 keeping the outer face of the pawl in contact with the cam, whereby upon the throwing of the throw-lever to its upward limit, the stamp-block will be automatically reversed so as to bring the newly inked bottom printing surface upward; and the just used top-printing surface downward.

6. In a stamping-device, a supporting base-piece; a spring retracted pivoted throw-lever, having a yoke; a stamp-block of cylindrical form carrying a soft-rubber out-

wardly concaved printing-face on either end; a cam-shaft or pin, revolubly securing the stamp-block in the yoke of the throw-lever; a spring normally maintaining the throw-lever in a raised position; an inking-pad supported by the base-piece immediately below the yoke; a cam-pawl pivoted to the base, a spring normally keeping the outer face of the pawl in contact with the cam, whereby, upon the throwing of the throw-lever to its upward limit, the stamp-block will be automatically reversed as to bring the newly inked bottom printing surface upward; and the just used top-printing surface downward.

7. In a stamping-device, a supporting base-piece; a spring retracted pivoted throw-lever, having a yoke; a stamp-block of cylindrical form carrying a soft-rubber outwardly concaved printing-face on either 70 end; a cam-shaft or pin having a substantially exteriorly figure 8 shaped cam revolubly securing the stamp-block in the yoke of the throw-lever; a spring normally 75 maintaining the throw-lever in a raised position; an inking-pad supported by the base-piece immediately below the yoke; a cam-pawl pivoted to the base, a spring normally keeping the outer face of the pawl in contact with the cam, whereby upon the throwing of the throw-lever to its upward limit, the stamp-block will be automatically reversed as to bring the newly inked bottom printing surface upward; and the just used top-printing surface downward.

8. A stamp-block having concavities at either end connected by an air-passage; an elastic printing-disk secured upon each of such concavities and sealing the same air-tight; whereby when one printing surface is brought into contact with the ink-pad, and an object to be printed is pressed upon the top elastic printing-disk, the air consequently compressed will force the like elastic printing-disk at the bottom on the ink-pad, and the same will be brought into contact therewith at all points, so as to thoroughly ink the printing-disk.

9. A stamp-block having concavities at either end connected by an air-passage; an elastic inwardly-concaved printing-disk secured upon each of such concavities and sealing the same air-tight; whereby, when one printing surface is brought into contact with the ink-pad and an object to be printed is pressed upon the top elastic printing disk, the air consequently compressed will force the like elastic printing-disk at the bottom on the ink-pad and the same will be brought into contact therewith at all points, so as to thoroughly ink such printing-disk.

10. In a stamping device a base, a pivot-ed lever mounted thereon, means for normally suspending one end of the lever above

the base, a stamp block having a plurality of outwardly faced opposed printing faces, said stamp block revolubly mounted on the suspended end of the pivoted lever, inking means carried by the base, the uppermost face of the block adapted to receive an article and print it during a downward movement of the pivoted lever, a downward movement of the said lever causing a contact of the bottommost printing face of the stamp block with the inking means.

11. A stamp block having recesses connected by an air passage, elastic printing members covering said recesses and sealing them air-tight, whereby the depression of one printing member will cause the distension of another printing member.

12. A stamp block having recesses connected by an air passage, concave elastic printing members covering said recesses and sealing them air-tight, whereby the depression of one printing member will cause the distension of another printing member. 20

13. A stamp block having a recess at each end connected by an air passage, elastic 25 printing members covering each of said recesses and sealing them air-tight whereby the depression of one printing member will cause the distension of another printing member.

FRANK EDWIN ANDERSON.
